(57) **CLAIM**

The ornamental design for an earphone, as shown and described.

DESCRIPTION

FIG. 1 is a front, top and left side perspective view of an earphone;

FIG. 2 is a rear, bottom and right side perspective view of FIG. 1;

FIG. 3 is a front view of FIG. 1;

FIG. 4 is a rear view of FIG. 1;

FIG. 5 is a left view of FIG. 1;

FIG. 6 is a right view of FIG. 1;

FIG. 7 is a top view of FIG. 1; and,

FIG. 8 is a bottom view of FIG. 1.

The broken lines shown on the drawings depict portions of the earphone that form no part of the claimed design.
